TIE SUPPORT

Thomas A. Pyros, Pittsburgh, Pa.

Application December 3, 1934, Serial No. 755,796

3 Claims. (Cl. 24—60)

This invention is a support for ties and an object of the invention is to provide such a support characterized by simplicity and economy of structure and which will serve to support admirably ties whether they be of the four in hand or bow type.

Briefly, the invention consists in the provision of a support consisting of a single body member provided for engagement with a collar button and also for engagement with the neck band of the collar and the tie in the region of the knot of the tie in a manner to insure a holding of the knot of the tie in proper position and thereby present a neat and attractive appearance.

The invention together with its objects and advantages will be best understood from a study of the following description taken in connection with the accompanying drawing wherein:

Figure 1 is a plan view illustrating the application of the invention, certain parts being shown in section.

Figure 2 is a plan view of the support.

Figure 3 is an edge elevational view thereof.

Figures 4 and 5 are longitudinal sectional views taken substantially on the lines 4—4 and 5—5 respectively of Figure 2.

Referring to the drawing by reference numerals it will be seen that the tie support comprises a body member 10 in the nature of a plate formed from metal or other suitable and preferably resilient material, the plate being of oblong structure and preferably having the corners rounded as clearly shown in Figure 2. To fit neatly in place the body plate 10 is longitudinally curved as shown.

At the center thereof the plate 10 is provided with an opening 11 adapted to engage the head of the collar button 12 in a manner clearly suggested in Figure 1. Adjacent the ends thereof the plate 10 has pointed prongs 13 punched or pressed outwardly therefrom, and these prongs, as clearly shown in Figure 1 engage the necktie 14 in the region of the knot 14a of the tie.

At the upper and lower edges thereof the body plate 10 at opposite sides of the transverse center

of the plate is slotted on diagonal lines radiating from the center of the opening 11 as a common center and at one side of the slits the portions of the plate 10 are slightly bent outwardly to thereby provide short prongs 15 that extend from the side of the plate 10 opposite to the prongs 13, and which prongs 15 engage the neck band 16 of the collar at opposite sides of the button 12 as clearly shown in Figure 1.

It will be apparent that with the plate 10 thus arranged in position with the opening 11 receiving the head of the button 12, the prongs 15 engaging the neck band of the collar, and the prongs 13 engaging the knot of the tie, the support 10 will remain in proper position and will serve to retain the tie, at the knot thereof neatly in place and in a manner to conceal the collar button 12 as is generally desirable.

Having thus described the invention, what is claimed as new is:

1. A necktie support comprising a body plate provided with a centrally located opening for receiving the head of a collar button, said plate having prongs projecting from one side thereof for engaging a necktie in the region of the knot of the tie, and other prongs projecting from the side thereof opposite to the first named prongs and adapted to engage the neckband of the collar as and for the purpose specified.

2. As a new article of manufacture, a necktie support comprising an oblong plate longitudinally curved and provided intermediate its ends with an opening, said plate having penetrating prongs projecting from one side thereof, and other penetrating prongs projecting from the side thereof opposite to the first named prongs.

3. A necktie support comprising an elongated longitudinally curved plate of resilient material, said plate being provided at its center with an opening for accommodating the head of a collar button, said plate also having integral prongs projecting from one side thereof, inwardly from the edges of the plate, and other prongs projecting from opposite edges of the plate.
